SIGN FOR A TELEPHONE BOOTH OR THE LIKE

William S. Barron, Decatur, Ga., assignor to Gladwin
Plastics, Inc., Atlanta, Ga., a corporation of Georgia

Filed July 11, 1961, Ser. No. 65,877

Term of patent 14 years

(Cl. D1—12)

FIGURE 1 is a front elevational view of a sign for a telephone booth or the like embodying my new design; FIGURE 2 is a top plan view of the same;

FIGURE 3 is an elevational view of the same taken from the left side; and

FIGURE 4 is an elevational view of the same taken from the right side.

The rear not shown is a mirror image of the front shown.

The dominant features of my design reside in the portions shown in full lines.

I claim:

The ornamental design for a sign for a telephone booth or the like, substantially as shown and described.
